ROBERT M. LAFEVER AND CHALAPHA G. GOSS, OF SALT LAKE CITY, UTAH

SAFETY RAZOR CARTON OPENER

Application filed June 2, 1931. Serial No. 541,583.

Our invention relates to the opening of packing cardboard cartons, and has for its object to provide a new and efficient tool for cutting out the top of a pasteboard packing carton so that the products may be removed therefrom with ease.

A further object is to provide an adjustable tool for cutting off the top of cartons and which tool may be so adjusted as to cut at different distances from the top of the carton or adjusted to cut different depths into the carton, depending upon the need.

A still further object is to provide a carton opener which is designed to use old safety razor blades or new blades having double cutting edges as desired, thereby making an economical device for the owner and making an economical device to manufacture as the razor blades may be purchased at any store.

A still further object is to provide a long lived device which may be used for many years by changing the blade whenever dull and which has a removable wing nut and bolt so that should the threads of the bolt be stripped another bolt may be inserted therein.

A still further object is to provide pockets in the body of the device to carry extra blades for the opener.

A still further object is to provide a carton opener which is so built as to allow the cutting blade to be placed therein from either direction to allow the device to be used by a right or left handed person and which blade may be adjusted in the device at various angles to provide the best cutting angle for the type of box or carton being opened.

These objects we accomplish with the device illustrated in the accompanying drawing in which similar numerals and letters of reference indicate like parts throughout the several views and as described in the specification forming a part of this application and pointed out in the appended claims.

In the drawing in which we have shown the best and most preferred manner of building our invention

Figure 1 is a perspective view of the device.

Figure 2 is a plan view of the base of the device.

Figure 3 is a plan view of the spacer used to raise or lower the blade for cutting different depths down the side of the carton.

Figure 4 is an inverted view of the cover plate of the device.

Figure 5 is a side elevation of the device with the cover plate and spacer removed.

In the drawing we have shown the base of the device as A, having a step cut B in one edge thereof to form a flange 2 on one side thereof. The base is then provided with a medially disposed hole through which a bolt 1 is screwed. The bolt 1 extends upward from the base to receive a spacer plate D, a cover plate C, and a wing nut 11.

On each side of the bolt 1 we provide a set of spaced apart bars 3 and 4, and 5 and 6, set in the base A so that the bars 3 and 4 are in alignment with each other, but so that a line drawn through the axis of the bars 3 and 4 would engage the step cut of the base at an acute angle. Likewise a line drawn through the axis of the bars 5 and 6 would also intercept the step of the base at an acute angle, but at approximately a right angle to that of the angle of the bars 3 and 4. These vertical bars are provided to carry the razor blades used in the device, the two bars being spaced apart sufficient distance to fit the two end holes of any type razor blade made to be used in a Gillette or Probak razor, or to engage in the slot of any type of safety razor blade having a medial slot therein such as the Durham Duplex razor blade. Spaced apart slots 7 and 8 are cut in the sides of the vertical bars to allow for some degree of side movement of the razor blades thereon so that the operator may move the blade to engage more or less of the box as desired to insure

being able to cut through very thick sided boxes or to cut through boxes having more than one thickness of cardboard. To enable the blade to be lowered so that a box having a heavier top may be opened we provide a spacer plate D having a medial hole 100

9 therethrough and spaced apart bar engaging holes 10 therethrough to enable the operator to place the plate on the base and then the razor blade thereover onto the top 5 of which the cover plate C is then placed and the entire assembly secured together by the thumb nut or wing nut 11.

The plate C is provided with holes 12 bored thereinto from the under or inner side 10 to receive the top end of the bars 3, 4, 5 and 6, the holes not extending through the plate C. A medial hole 13 allows the central bolt 1 to be passed up through the plate C.

The base A is provided with depressions 15 or sockets 14 and 15 in the ends thereof to receive extra blades and to carry such blades therein. The back side of the base and the plates have hand engaging extensions 16 and 17 and 18 formed thereon to allow the 20 operator to hold onto the device more easily.

The operation of the device is as follows:—

The operator takes hold of the device and laying the flange 2 flat on the top of the box 25 engages the step cut B along the side of the box and draws the blade G into the box along the side thereof which blade cuts off that side of the box. The operator then turns the corner and draws the blade along the 30 next side and so on until the top is either entirely out or until three sides have been cut free and the top may then be raised up bending the fourth side and using the top as a hinged lid for the carton, with the 35 fourth uncut side acting as the hinge.

A left handed person must place the blade in the device so that it may be used with the left hand and in order to enable the user to know which setting is for which hand 40 the letters "L" and "R" are stamped into the base, indicating the side on which the cutting blade H is to be placed for the different uses.

If it is desired to cut off a box top having 45 a very thick lid the spacer plate D is placed adjacent the base A and the cutting blade G is placed between the plate D and the cover plate C. For most boxes the blade is between the plate D and the base A.

50 For boxes or cartons requiring a deeper cut the blade may be extended out by adjustment in the slots 7 or 8 as necessary, the slots 8 being for use when the blade is between the spacer and the cover plates, and 55 the slots 7 being for adjustment when the blade is between the base A and the spacer plate D.

Having thus described our invention we 60 desire to secure by Letters Patent and claim:

65 In a device of the class described the combination of a base having a step cut in one longitudinal edge thereof and an extended hand engaging portion on the opposite longitudinal edge thereof; sockets in said base 65 in which extra cutting blades may be car-

ried; sets of spaced apart aligned lugs extended from the side of said base adjacent said step cut, one set being to hold the blade to cut with one edge and the other set to hold the blade to cut in the opposite direction with the opposite cutting edge; a cutting blade having both edges sharpened and adapted to fit over said lugs; slots in said lugs to allow for angle adjustment of said blade on said lugs; a spacer plate to be carried on said base on either side of said blade to space the blade from the step cut the proper space for opening either light or heavy cartons; a cover plate carried on said base over said spacer plate having sockets 70 on the inner side thereof to engage with the ends of the lugs; a medially disposed bolt passed through said base and cover plate; and a wing nut to apply pressure to the cover plate to hold the blade in fixed relation to the step cut of said base.

In testimony whereof we have affixed our signatures.

ROBERT M. LAFEVER.
CHALAPHA G. GOSS.
